UNITED STATES PATENT OFFICE.

RYERSON D. GATES, OF CHICAGO, ILLINOIS.

PULVERIZING-MACHINE.

SPECIFICATION forming part of Letters Patent No. 286,290, dated October 9, 1883.

Application filed April 26, 1883. (No model.)

To all whom it may concern:

Be it known that I, RYERSON D. GATES, of Chicago, in the county of Cook and State of Illinois, and a citizen of the United States, have invented a new and useful Improvement 5 in Pulverizing-Machines, of which the following is a specification.

My invention relates especially to certain novel and useful constructions and combinations of parts, whereby the pulverizing-machine patented to me in the United States June 27, 1882, and December 19, 1882, numbered, respectively, 260,092 and 269,404, is rendered more effective, and greater convenience is afforded for repairing and adjusting it, and also improved means are provided for driving the screen and pulverizing-rollers, while the means for connecting the parts are improved.

In the accompanying drawings, Figure 1 is a vertical cross-section, in the line $x' x'$ of Fig. 2, through the shafts of the rollers and the supporting-foundation of the mill, showing also the improved roller-pulverizer case in side elevation. Fig. 2 is a vertical sectional view in the line $x x$ of Fig. 1, and showing portions of the machine in elevation. Fig. 3 is a side view of the upper section, the removable side section, and one of the lower sections, to which the removable side section 25 is bolted, and upon which the other side section is applied by bolting it thereto or casting it with said lower section, said parts of the inclosing case or frame being shown as slightly separated from one another, the sills 30 of the foundation-support of the mill being shown by dotted lines. Fig. 4 is a detail side view of the lowest section of the inclosing-frame or outer case, revolving screen, interior hopper, elevator-buckets, and friction driving-rollers of the screen; also, a vertical cross-sectional view of the pulverizing-rollers, tie, and supporting-rods. In this view the outer inclosing frame or case and the inner shells of 40 the screen are supposed to be removed. Fig. 5 is a detail side elevation of the inner shells tied together, and a vertical cross-section of the journals of the pulverizing-rollers. Fig. 6 is a vertical central section of Fig. 5. Fig. 7 is a detail vertical central section of the revolving screen with the inner shells removed. Fig. 8 represents an elevator-bucket as it appears in front and end elevation. Fig. 9 is a

diagram of the driving-gearing and revolving screen, the driving-pulley and balance-wheel being left off. Fig. 10 is an enlarged sectional view of a portion of the screen, showing an elevating-bucket, the two grooved ring-plates of the screen-frame, a clamping-rod, grooved stay, and agitating-bar of said frame, and the wood-tacking strips of the ring plates and bars. Fig. 11 is an edge elevation of the outer inclosing case or frame, and Fig. 12 is a similar view of the inner shells of the screen.

In the machine represented by the accompanying drawings two sets or pairs of pulverizing-rollers, $G G'$, are employed, the material passing directly from one to the other set through a hopper, G^2 , and then dropping into the revolving elevator and screen $H H'$. The frame or outer case, A , with its inner shell- 65 plates, $B B'$, is so constructed that it can be easily taken apart to get to the pulverizing-rollers $G G'$ and elevator-screen $H H'$ in case of repairs being necessary. The upper part, a , of said frame or case A is removable, like a 70 cover, being fastened by flanges and bolts, as at u , to the intermediate flanged parts, $a' a'$, which in like manner are fastened to the flanged part a'' , which in turn is fastened by flanges and bolts, as at a''' , to the lowermost part, a^4 , 75 all in the manner shown.

The plates $B B'$ of the inner shell are constructed separately, each being formed of two pieces with bolting-flanges, so as to be bolted together after they are slipped upon the journals of the pulverizing-rollers, as illustrated at U in Figs. 4, 5, 6, and 12. These shells are fitted over the journals of the pulverizing-rollers, with their respective pieces unbolted at U , and then the pieces are bolted together. One 85 of the shells, B , can be removed over the left-hand ends of the journals after the section a and the section a' of the inclosing case or frame A are removed, it only being necessary to unbolt the pieces at U and separate the shells at n . The elevator-buckets H' are adjustable to any desired angle on their pivot ends f after slackening the clamp-bolts l , which hold them from turning while in use. The ring-plates h^2 of the screen H are clamped by the bolts l 90 against the ends of the buckets H' and tenon ends of grooved metal bars h . This manner of constructing the screen-frame of separable plates and bars and of making the elevating-

buckets separately from the screen-frame enables me to repair the worn portions, and thus avoid the extra expense of renewing the screen entirely, as is necessary when the frame is cast in one piece. The bars h , by being filled with wood, form a foundation upon which to fasten the wire-gauze, and also serve for stiffening the screen and for agitating the substances as they are being carried up by the revolving screen-elevator. The screen is revolved by friction-rollers $b^2 b^4$ on shafts $b' b'$, which shafts are driven by belts $c' c'$, set in motion by the shaft M^5 , which drives the toothed gearing of the pulverizing-rollers, as will be hereinafter described. The frame or outer inclosing-case, A, is circular in form, and provided with outside feed-hoppers, O O, one on each side, and with an interior hopper, G^2 , the latter being suspended upon cross screw-rods m by means of hook-shaped brackets m^9 , formed on the hopper. The lower section, a^2 , of the frame or outer case is tapered or funnel-shaped, and open for the discharge of finely-pulverized substances.

The sections $a' a^x a^2$ of the frame or outer case, A, have laterally-extending flanges $a^5 a^6$ formed on them, and when they are brought together from the separated condition shown in Fig. 3 to a united condition, as shown in Figs. 1, 2, and 11, fastening-bolts u can be passed through the flanges outside of the case, and thus a strong and firm frame or outer case produced, and which is readily divisible. On the lower section, a^2 , bolting-flanges a^8 are provided, and these serve for sustaining the pulverizing-machine upon the foundation-sills of the frame P. The lowermost section, a^2 , is formed with a slightly-overlapping flange, a^9 , and within this flange the lower extremity of the section a^2 extends, and bolts a^{10} are passed through the flange and into the section a^2 , as shown. At the bottom of this section a^2 oblong openings t are provided, so as to allow of its being fitted over the friction-roller shafts, or to permit it to be withdrawn from said shafts.

Upon the top and bottom (see Fig. 2) of each of the side sections, $a' a^x$, bearing-brackets d^4 are formed, and the boxes $d^8 d^6$ for the journals $g^5 g^6$ of the pulverizing-rollers G G', together with devices S for adjusting the movable journal-boxes, are applied upon these brackets in the manner shown.

The adjusting devices, with blocks and plates for retaining the boxes in proper position, are shown as the same as in my United States patent for pulverizing machine, No. 269,404, hereinbefore mentioned, or they may be of any other suitable construction.

The section a of the outer case or frame is provided with oblong openings d^7 , and the side sections, $a' a^x$, with circular, nearly circular, or other properly-shaped openings, d^8 , for the journals of the pulverizing-rollers, while the section a^2 has oblong openings, t , as hereinbefore described, to admit the shafts or journals of the friction-rollers. The respective openings are shaped to suit the necessary adjust-

ments of the journals of the pulverizing-rollers and the friction-rollers, as will be seen by referring to Figs. 1, 2, and 3 of the drawings.

The portion of the periphery of the outer case which laps over the joint between sections a' , a^x , and a^2 and abuts against the periphery of sections $a' a^x$ is formed upon the section a^2 , as indicated at d^6 , and thus a completely-closed circular chamber can be formed notwithstanding the portions $a' a^x a^2$ are constructed separately, and this will be the same whether only one or both of the side sections, $a' a^x$, are constructed separately from the section a^2 ; and with such construction the section a^2 is removable by sliding it off the journals of the pulverizing-rollers without disturbing the gearing on the right-hand side of the inclosing case or frame A.

The pulverizing-rollers G G' are formed with grinding-shells m^3 , of hard white or chilled metal, which may, if necessary, be prepared in the casting with soft linings, which can be bored tapering and fitted upon tapered hubs m^4 , whereby a wedging fit can be secured, as indicated at s^1 , between the shells m^3 and said hubs m^4 when the shells are drawn upon the hubs by bolts. The shells, being bored tapering and fitted upon tapered hubs, are drawn up and held firmly by means of the screw-bolts m^5 , which pass through openings formed, respectively, half in the hubs m^4 and half in the shells m^3 , the heads of the bolts at one end and the nuts at the other binding, respectively, upon the ends of the shells and ends of the hubs, as shown in Figs. 2 and 4. Both sides of the outer case, A, are alike, and the inner shell-plates, B B', are also alike; but the journals of the rollers on one side are lengthened and receive upon them matching gear-wheels $M M'$, and one shaft of one pair receiving a gear-wheel, M^2 , and the other shaft of the other pair a gear-wheel, M^3 , which wheels are driven by an intermediate gear-wheel, M^4 , on a center shaft, M^5 , said center shaft being boxed at one end upon the outer casing, A, and passed through a spider, M^6 , which supports and sustains the extended ends of two of the journals of the rollers G G'. The shaft M^5 being sustained upon the frame P and casing A, and the spider being fitted loosely on this shaft, and is thereby enabled to hold up and apart the said ends of the journals of the rollers G G'.

On the shaft M^5 a gear-wheel, N, is provided, and this wheel is driven by a smaller gear-wheel, N' , on the pulley and balance-wheel shaft N^2 . The shaft M^5 , by being provided with a bearing or box, M^{10} , on the inclosing-case A, is partly supported by said case, while it, with the shaft N^2 , is also supported by the frame P. The shaft b^3 , while being supported upon the frame P, is supported upon the case A, as will be presently shown. The shaft M^5 carries a pulley, M^7 , and from this pulley a belt, c , passes to a pulley, c' , of a shaft, b^3 . The shaft b^3 leads into the case A, being boxed at b upon the lower section, a^2 , of said case.

Upon the shaft b^3 and a shorter shaft, b' , driving friction-rollers b^2 and b^4 are applied, and these shafts are connected by means of a belt, c , passed from pulley c^3 on shaft b^3 , and a pulley, c^4 , on shaft b' , as shown in Figs. 2 and 9.

The revolving elevating-screen is arranged centrally within the case A upon the driving friction-rollers b^2 b' , its shouldered portion r resting upon the rollers, while its screen or wire-gauze portion revolves between the same. The elevating-buckets H' of the screen being made separate from the ring-plates h^2 of the screen, and their ends formed with short journals f , which fit into sockets or holes formed in said plates h^2 , can, by slackening the nuts of the clamping-bolts l , be changed in position, and by these bolts again clamped tightly between the ring-plates when they have been set at the proper angle for elevating the substances and discharging them at the top of the case for a second grinding operation. The buckets do not turn on their journals when in operation; but by providing them with the journals f and making them separate from the screen they can be set with the proper pitch or can be adjusted very nicely, so as to be caused to discharge more or less freely, accordingly as the speed at which the screen is operated may require, and after being adjusted they can again be made rigid with the screen-frame. The tenons h^5 of the bars h enter sockets in the ring-plates h^2 when the clamp-bolts are drawn up tight, and thus will be kept in position when in operation. Into the grooves g of the bars wooden strips g' are fitted, and these strips afford a suitable foundation, into which tacks or screws may be inserted for securing the wire-gauze upon the metal frame. In the peripheries of the ring-plates h^2 of the screen, grooves g^2 are formed, and into these grooves wood g^3 is placed, so as to afford a foundation into which the tacks or screws which secure the edges of the wire-gauze in place may be inserted.

The shell-plates B B' slide over the journals of the rollers G G', and are supported on rods m , held by the outer case or frame, and while in position they close the side openings of the ring-plates of the screen. They have apertures t^2 t^3 through them, coinciding with apertures d^2 d^3 for the journals of the rollers; also, passages o^2 at their upper edges, coinciding with the two outside feed-hoppers, O, and are connected together so as to almost touch against the ring-plates of the screen, or so as to stand a short distance away from the same, by means of bolts n , which cause them to slide on the rods m . The bolts n may be provided with adjusting shoulder-nuts n' , and they may be either rigidly drawn up against the shell-plates or have their heads or nuts cushioned against spiral springs. I prefer the rigid manner of fitting the bolts, as shown. The shell-plates B B' of the screen confine the substances to be pulverized within the screen, and thus prevent escape of the same, except when they are finely pulverized, when they

are discharged through the meshes of the wire-gauze. The revolution of the screen is produced by a positive motion imparted to the friction-rollers by means of the belts and pulleys described, set in motion by the power-shaft, which sets in motion the gearing for driving the pulverizing-rollers.

The different apertures for the journals and shafts may be closed on the outside of the case A by means of spring-pressed disks or plates, such as t' , in order to make everything as tight and close as possible, in the same manner as in my hereinbefore-mentioned patents.

The hopper G² is placed upon the rods m , and is supported thereby between the upper and lower sets of pulverizing-rollers, and by its tapered sides it properly conducts the substances between the lower set of rollers, as will be clearly seen from the drawings.

I would state that the shell-plates might be made without a division at U by making the division s^2 low enough down to allow the shell-plates to be slipped laterally into the outer case, and to permit the plate B to be slipped out of the case when the cap-section a has been removed. The section a^2 on right-hand side of case A may be cast with the part a^2 without altering the general plan of my invention, and therefore I do not confine myself to having both portions a^2 a^3 constructed separately from section a^2 , although it is best for packing and transportation to have the sections a^2 a^3 separate from section a^2 . If the section a^2 is cast with section a^3 , it will be in all respects substantially as represented, except that the division-line s^2 will not be formed, nor the horizontal bolting-flanges a^6 and a^7 provided on the right-hand side of the sections a^2 a^3 , there being only the oblique bolting-flanges a^6 with the brackets d formed on the said section a^2 .

The part a^2 might be modified by bolting the journal-boxes of the friction-rollers b^2 b^4 directly upon the lower edge of section a^2 , so that by unbolting these boxes access to the shafts b' and b^3 could be had, or said shafts and friction-rollers lowered for removal or other purposes; and the gear-wheel N, pinion N', shaft N', fly-wheel, and pulley may be dispensed with, and a pulley placed upon the shaft M², which may for this purpose be extended, and the machine driven directly from this pulley.

In practice my improved case A, inner shell-plates, B B', revolving elevating-screen, driving friction-rollers, and interior hopper may be so modified in construction as to be adapted for use in combination with either one, two, three, or more sets or pairs of pulverizing-rollers.

What I claim as my invention, and desire to secure by Letters Patent, is—

1. The pulverizing-roller case A, having the separately-constructed sections a and a' , and the side portion, a^2 , which are provided with oblique flanges, and the fastening-bolts, the upper section, a , being of cap form and separably united to the side section, a' , and portion a^2 by said bolts and oblique flanges, whereby

the upper section of said case is removable in an upward direction, substantially as and for the purpose described.

2. The pulverizing-roller case A, having the 5 separably-constructed sections a a' a'' and the portion a^* , which are provided with flanges, and fastening-bolts, the side sections, a' a^* , being provided with journal-bearing supports, whereby a section a' and the journal-bearings 10 on a side of the outer case or frame are removable laterally after said section has been upwardly removed, substantially as and for the purpose described.

3. The pulverizer-case A, having separate 15 sections a^2 and a^3 , united by a lapping flange and bolts, the section a^3 being movable downwardly, substantially as and for the purpose described.

4. The pulverizing-roller case A, formed of 20 the top section, a , side or middle sections, a' a^* , and lower sections a^2 and a^3 , in combination with the pulverizing-rollers, the driving friction-rollers, and the journals or shafts and boxes of said rollers, substantially as and for 25 the purpose described.

5. The combination of inner shell-plates, 30 B B', supporting-rods m , uniting-bolts n , the sectional case A, revolving-elevating-screen H H', and pulverizing-rollers, substantially as and for the purpose described.

6. The combination of the interior hopper, 35 G², and supporting-rods m , with the outer case, A, provided with outside feed-hoppers, O, the the rollers G G', and revolving screen H, substantially as and for the purpose described.

7. The revolving screen provided with ring- 40 plates h^2 , clamping-rods Z, elevator-buckets H',

having short journals and being adjustable between the clamping-plates, substantially as and for the purpose described.

8. The revolving screen provided with ring- 45 plates h^2 , clamping-rods Z, and separately-constructed bars of metal h , which are filled with wood, as g' , and are clamped between the said ring-plates, substantially as and for the purpose described.

9. The revolving screen provided with the 50 ring-grooved plates h^2 and wood g^3 , substantially as and for the purpose described.

10. The revolving screen provided with the 55 ring-plates h^2 , bars h , and the wood fillings g' and g^3 , substantially as and for the purpose described.

11. The combination of the pulverizing-rollers, a casing therefor, a revolving elevating- 60 screen inclosing said rollers, the gearing for the pulverizing-rollers, and the gearing M^7 c c' c^4 c^5 c^6 , shafts b' b^3 , and friction-rollers b^2 b^4 , for driving the revolving elevating-screen, substantially as and for the purpose described.

12. The combination of the pulverizing-rollers G G', the revolving elevating-screen H H', the inclosing roller-case A, and the friction-rollers b^2 b^4 , for frictionally driving said screen, substantially as and for the purpose described.

13. The combination, with the rollers and inclosing-case A, of the central shaft, M^5 , gears M M' M^2 M^3 , journals g^5 g^6 , spider M^6 , gears N N' , and pulley-shaft N^2 , substantially as and for the purpose described.
